CLAMP FOR CURB FORM

Frank Torrelli, 40 Arthur St., Cheektowaga, N.Y.
Original application July 5, 1955, Ser. No. 519,699.
Divided and this application Oct. 8, 1957, Ser. No.
688,983

1 Claim. (Cl. 25—118)

This invention relates to a clamp for forms or molds for the construction of poured concrete curbs.

This application is a division of my copending application for curb form Serial No. 519,699 filed July 5, 1955, now Patent No. 2,948,943.

One of the objects of the invention is to provide a clamp for sectional forms for poured concrete curbs which are easily assembled, are securely held together and are easily stripped from the curb when the concrete curb has set.

Another object is to provide a simple and easily applied and removed clamp for holding the main parts of curb form sections together.

Another object of the invention is to provide a clamp for form sections for making concrete curbs which is of rugged and durable construction, in particular to withstand the rough usage to which it is necessarily subjected, and which are also inexpensive to maintain.

Other objects and advantages will be apparent from the following description and drawings in which:

FIG. 1 is a transverse, sectional view through an assembled curb form constructed in accordance with the present invention.

FIG. 2 is a fragmentary top plan view of the form assembled as shown in FIG. 1.

FIG. 3 is a fragmentary, front elevational view of the curb form assembled as shown in FIGS. 1 and 2.

The concrete form to which the clamp of the present invention is applied, is designed for use in the construction of curbs for streets, roads and the like. The form sections compose a mold adapted to be staked to the ground and having an open bottom and top. The two sides of the curb are molded by form sections which are designed to be joined end to end to produce a curb of the desired length. Each section of the form comprises as principal elements three rails, which are preferably sheet steel channel members. In each form section, the rear face of the curb, i.e., the side remote from the road or street, is molded against a single upright horizontal rail 20. On the front, each section of the form comprises a lower horizontal rail 21 that is also preferably upright and an upper horizontal rail 22 which rests on the rail 21 and is preferably inclined rearwardly.

The rear or back rail 20 comprises a web 23 having longitudinal top and bottom flanges 24 and 25, respectively. The outer edge of each of the flanges is preferably turned vertically and inwardly as shown at 26 and 27 to provide additional strength and rigidity for the channel member 20 and an end block 31 is secured, by suitable means such as welding, within the channels formed between the inturned edges 26 and 27 of the flanges 24 and 25 and the web 23 at one end of each of the rails 20. Each of the blocks 31 has a portion projecting longitudinally from the corresponding end of the rail 20, the outer end of the projecting portion being beveled so as to be pointed, as indicated at 32, thereby to facilitate the insertion of this block into the end of another mating rail member 20. Each of the lower front channel members or rails 21 can be of similar construction to the back rail 20, having a web 42 and longitudinal top and bottom outwardly projecting lateral flanges 43 and 44. The edges 46 and 47, respectively, of the flanges 43 and 44 are turned inwardly and preferably aline with each other parallel to the web 42. Each

2

of the rails is also provided at one end with an end block 48 similar to the block 31, the outwardly extending portion of each block 48 being also pointed, as indicated at 49, to facilitate insertion of this block into the next succeeding mating rail 21.

The curb form is shown as including a bracket or clip, indicated at 52, for receiving the stakes 54, these stakes being driven into the ground and cooperating with similar stakes 54 at the back of the form both to hold the form 10 reliably positioned on the ground and also to hold the sections of the form in assembled and properly spaced relation to one another. Each stake bracket or clip 52 is secured to the end of the rail 21 opposite its block 48 and within the channel provided by the web 42 and 15 the flanges 43 and 44. It consists of an L-shaped bracket having a leg 55 which projects outwardly from the web 42 and a leg or flat finger 56 extending from the outer edge of the leg 55 in a direction generally parallel with the web 42. The bracket is provided with an attaching flange 57 which can be secured, as by welding, to the front or channel face of the web 42. The leg or flat finger 56 of the stake attaching bracket or clip 52 is set outwardly from the vertical plane of the flanges 46 and 47 such distance that each stake 54 can be driven 20 downwardly and have one of its sides engaging the flanges 46, 47 and its opposite side engaging the leg or flat finger 56 of the bracket or clip 52. This fit is preferably quite snug, in fact, it is desirable that the bracket 52 be sprung outwardly slightly to accommodate the stake and for this 25 purpose, the outer vertical extremity of the leg or flat finger 56 is preferably provided with an outwardly curving lip 58 as best shown in FIG. 5.

The front surface of the concrete curb, according to the present invention, is also preferably formed with a 35 rearwardly inclined top portion. The mold for this portion of the front surface is provided by the upper front channel members or rails 22, each of which is of generally similar form to the rails 20 and 21 and has a web 60, longitudinal top and bottom outwardly projecting flanges 61 and 62, the edges 63 and 64, respectively, of which are preferably turned inwardly in opposed facing relation. Each rail 22 also preferably has a block 65 welded in one of its ends and each block 65 has a pointed end 66 projecting outwardly from its rail 22 and 40 to be inserted into the end of a succeeding mating rail 22. The bottoms of the channel members or rails 22 rest on the tops of the lower front rails 21 and the rails 22 are supported in the desired inclined position by a 45 division and spacing plates 68 which are placed transversely between the front and rear channels or rails at regular intervals.

Each of the division plates 68 is preferably formed of sheet metal of substantial thickness so as to be stiff and resist bending and the main portion of each plate is shaped 55 as a rectangle with the upper front edge being inclined as best shown at 69, at the angle desired for the inclined top of the curb. The length and width of the division plate are the same as the height and thickness, respectively, of the concrete curb which is to be constructed. A tab or ear 60 70 can be formed at the top of each of the division plates 68 and is shown as provided with a hole 71. Each of the division plates 68 can also be provided on the upper rear edge thereof with a block 72 of substantial size which projects rearwardly from the plate and is adapted to rest 75 on the upper flange 24 of the rear rail 20 to hold the division plate in proper position. The blocks 72 are preferably rigidly attached, as by welding, to the upper edges of the division plates 68.

The rails 20, 21 are held against the rear and front sides 70 of the division plates 68 by ties constructed as best shown in FIG. 6, these ties also holding each companion pair of stakes 54 against spreading or other displacement.

Each of these ties, indicated generally at 75, is in the form of a rigid metal strap 77 having one end reversely bent to provide an end hook 76, this hook being of a size to embrace the corresponding stake 54, the latter being shown as being round in cross section. The opposite end of each strap 77 is bent laterally to provide a flange 78 which extends from the same side of the strap 77 as the hook 76. Each strap also has welded thereto an L-shaped bracket 79, this bracket having a leg 80 which is arranged in parallel spaced relation to the flange 78. The spacing of the leg 80 from the flange 78 is approximately equal to the thickness of each stake 54 and the flange 78 and leg 80 are provided with alining holes 81 and 82, respectively. These holes are arranged to receive a tapered pin or nail 83. The tapered shank 84 of this pin enters the holes 81, 82 and forms a wedge or cam for wedging or camming the corresponding stake 54 against the back of the tie 75. To facilitate removal, the pin or nail is provided with a head 86.

The upper front channel members or rails 22, the flat webs 60 which form the inclined upper surface of the curb front, are held in position against the inclined front edge portions 69 of the division plates 68 by metal U-clamps 85 embodying the present invention. Each clamp is made in the form of a rigid metal strap and comprises a horizontal cross part 87, a depending vertical rear leg 88 and a downwardly and forwardly inclined front leg 89. It is an important feature of the invention that the lower extremity of the front leg 89 terminates in a reversely bent or hooked portion 90 which inclines downwardly and rearwardly, that is, downwardly and toward the rear leg 88. This leg 88 is disposed substantially perpendicularly to the cross part 87 while the other leg 89 extends from the cross part 87 at an obtuse included angle which is preferably generally the same as the included angle to the vertical formed by the inclined edge portion 69 of each of the plates 68 and hence the included vertical angle of the rails 21 and 22.

In using the U-clamp 85, the rails 22 are placed in position with their lower edge flanges 62 resting on top of the upper flanges 43 of the lower front rails 21, and the rails 22 are inclined rearwardly so as to rest against the inclined edges 69 of the division and spacing plates 68. The U-clamps 85 are placed over the tops of the rails 20 and 22, with a block 92, preferably of wood, placed in the channel of the rear section 20 to be engaged by the rear leg 88 of the U-clamp. The front leg 89 of each U-clamp is then stressed forwardly and the U-clamp pushed down until its hook 90 passes below the flange 46 of the lower front rail 21. This hook or reversely bent portion 90 springs into firm engagement with the flange 46 and extends thereunder so as to resist any tendency for the U-clamp to work itself upwardly due to its wedge shaped form.

In erecting or setting up curb forms as above described, the following procedure has been found convenient although other sequences of steps may be used.

A rear channel member or rail 20 and a lower, front channel member or rail 21 are placed on edge on the graded ground in upright spaced relation and division plates 68 are placed between them at suitable intervals with the blocks 72 thereof resting on the top of the rail 20. Pairs of stakes 54 are then driven into the ground along the outer sides of the front and rear rails 20 and 21. Each front stake is driven downwardly in contact with the flanges 46 and 47 of the lower front rail 21 and also in contact with the inner face of the leg or flat finger 56 of the stake bracket 52 welded to one end of the lower front rail 21. Each rear stake 54 is driven to aline with its companion front stake 54 and is driven downwardly in contact with the flanges 26 and 27 of the corresponding back rail 20.

Each pair of stakes is then connected and alined with a tie 75. This connection is quickly effected by hooking the hooked end 76 of the tie over one of these stakes and

then swinging the tie horizontally to place the companion stake 54 between the flange 78 and the leg 80 of the bracket 79. Each tie is then latched by driving the wedge shank of the pin or nail shown in FIG. 7 through the holes 81, 82 so as to confine the corresponding stake 54 in the hook provided by the flange 78 and leg 80. Any irregularity in driving the stakes is overcome by the requirement that the front stake 54 be in contact with the flanges 46 and 47 of the lower front rails, this being assured by the stake bracket 52, and by the requirement that the upper end of the rear stake 54 be in contact with the flanges 26 and 27 and also in proper position with reference to the companion front stake 54, this being assured by the tie 75.

15 The upper front rails 22 are then placed on top of the lower front rails 21 and are laid back so as to engage with the inclined edges 69 of the division plates 68. A wooden block 92 is then placed against the rear face of the web 23 of the rear rail 20 in line with the division plate 68 and the rear leg 88 of a U-clamp 85 is placed against the inner face of the block, projecting downwardly along the outer side of the back rail 20 across the upper flange 24 thereof. The front leg 89 of this U-clamp is then stressed forwardly and the U-clamp pushed down 25 to extend lengthwise of the inclined edge 69 of the adjacent spacing plate 68 and along the outer side of the inclined rail 22 and across both flanges 63 and 64 thereof. When the hooked end 90 of the front leg passes below the flange 46 of the lower front rail 21, the U-clamp is released so that this hook 90 hooks under this flange 46, as best shown in FIG. 1, thereby to prevent the U-clamp from working its way upwardly due to its wedge shaped form and its inherent resiliency.

Concrete can then be poured in the mold provided by 35 the assembled forms. When the concrete has taken its initial set, the U-clamps 85 can be removed to permit taking off the upper front rails 22 so that the upper front and top of the concrete curb can be brushed and smoothed or finished while the concrete is still fresh. After the concrete has set, the wedge pins or nails 54 can be withdrawn from the holes 81, 82 whereupon the tie bars 75 can be swung horizontally with the hooks 76 as a pivot, thereby to free the corresponding stake 54 from the flange 76 and leg 80 of each tie bar. Each tie bar 75 can then 40 be moved longitudinally to free its hooks 76 from the opposite stake.

With the rear rail 20 still in position, a tool can be inserted in the hole 71 of each division plate 68 and the flange 24 of the rail 20 used as a fulcrum to draw the division plate upwardly. Following this, the stakes 54 can be pulled and the rails 20, 21 and 22 stripped from the form. It will be noted that the division plates 68 serve not only to space the rails 20, 21 and 22 of the forms, but also provide expansion joints at intervals along the length 55 of the curb.

From the foregoing, it will be seen that the legs of the U-clamp 85 insure that these clamps when applied as shown in FIG. 1 are securely held in position and will not work themselves up.

60 I claim:

In a form for concrete curbs or the like having a relatively high upright back rail, a relatively low upright front rail, a plurality of spacing plates between said rails and each having an inclined edge extending upwardly and rearwardly from the upper edge of said front rail, and an inclined rail disposed against said inclined edges of said spacing plates and supported on said front rail, each of said rails being of channel form in cross section with its edge flanges projecting outwardly; the combination therewith of U-clamps for holding all of said rails against said spacing plate and each comprising single strap of metal bent to provide a horizontal upper part, a vertical depending rear leg projecting downwardly along the outer side of said back rail and projecting across the upper flange of said back rail, a downwardly and forwardly in-

clined front leg projecting downwardly lengthwise of said inclined edge of the adjacent spacing plate along the outer side of said inclined rail and across both the flanges of said inclined rail, and a hook at the lower end of said front leg and extending downwardly and rearwardly to engage and extend under the upper flange of said front rail, said hook being at an included obtuse angle to said front leg which is generally the same as the included angle to the vertical formed by the inclined edge of each spacing plate.
